X-RAY APPARATUS

Georg S. Mittelstaedt, Brooklyn, N. Y.

Application September 9, 1955, Serial No. 533,406

11 Claims. (Cl. 250—93)

An object of this invention is to emit a beam of ionizing waves, and to send a current of electricity along said ionized path.

Another object is to emit X ray beams, intersecting each other, thereby concentrating and intensifying the rays at the intersection point.

Still another object is to emit two intersecting ionizing X ray beams, and to connect the paths of said beams to an electric source, thereby imparting an electric current into said ionized paths, and to break the circuit at the intersection point of said X ray beams.

The above and other objects will become apparent in the description below in which characters of reference refer to like-named parts in the drawing, which illustrates the basic principle of the invention.

Referring in detail to the drawing, the numerals 1 and 2 indicate X ray machines emitting ionizing X ray beams 5 and 6 from X ray tubes 3 and 4, said beams intersecting each other at 7. The numeral 8 indicates an electric source having terminals 9 and 10. Connected to these terminals are conductors 11 and 12, which extend into the paths of X ray beams 5 and 6, thereby closing an electric circuit. The numeral 13 indicates a device to oscillate or otherwise move emission tube 4, to separate the beams and thereby break the circuit. 14 indicates a device to oscillate or otherwise move the windowed emission tube sleeve or shield 15.

The concentration and increased intensity of the X rays at the intersection point has obvious medical and industrial advantages. Viewing and testing is improved, and the intensified intersection area can be treated without harm to the surrounding tissues. The collision of X rays with electrically charged particles in the intersection area further increases the efficiency of the device.

The paths of the intersecting X ray beams may be electrified by connecting them to an electric source, and the circuit may be broken intermittently at the intersection point, thereby creating circuit breaking effects at said intersection point, such as minute sparking, burning and associated effects. The circuit may be opened and closed anywhere by moving the beams, by emitting a beam intermittently, by deflection or reflection, or by any other circuit breaking means. The X ray apparatus, or any part thereof, such as the emission tube, or its shield or window, may oscillate from side to side, or back and forth, or may rotate or move in any suitable manner to unite and separate the X ray beams.

Any type of ionizing rays may be utilized.

The invention may be used in any pertinent field. It may be used to view, test, affect and treat organisms, organs, objects and matter. Medically it may be used to cauterize, sterilize, and to combat diseases. The de-

2

vice may also be used as an igniting and exploding means, and to create atmospheric, electrical, mechanical and other disturbances. Atmospheric changes or disturbances may be caused by electric discharges between ionized beams of opposite electric signs.

Changes in form and construction may be made without departing from the spirit or scope of the invention.

I claim:

1. An apparatus adapted to send forth intersecting beams of ionizing short waves, an electric source communicating with the matter within said beams of ionizing radiation, thereby closing an electric circuit, and a means to move said beams apart and together for breaking and making said electric circuit, said circuit making and breaking means comprising a rotatably mounted sending apparatus and a means to rotate said sending apparatus.
2. A system according to claim 1, in which the circuit making and breaking means comprises a rotatably mounted emission tube and a means to rotate said emission tube.
3. A system according to claim 1, in which the circuit making and breaking means comprises an emission tube, a rotatably mounted shield about said emission tube and a means to rotate said shield.
4. A system according to claim 1, in which the circuit making and breaking means comprises an emission tube, a shield about said emission tube, a rotatably mounted window in said shield and a means to rotate said window.
5. A system according to claim 1, in which the circuit making and breaking means comprises a movably mounted sending apparatus and a means to move said sending apparatus to and fro.
6. A system according to claim 1, in which the circuit making and breaking means comprises a movably mounted emission tube and a means to move said emission tube to and fro.
7. A system according to claim 1, in which the circuit making and breaking means comprises an emission tube, a movably mounted shield about said emission tube and a means to move said shield to and fro.
8. A system according to claim 1, in which the circuit making and breaking means comprises an emission tube, a shield about said emission tube, a movably mounted window in said shield and a means to move said window to and fro.
9. An apparatus for sending forth intersecting beams of ionizing short waves, an electric source for electrifying said beams of ionizing radiation, thereby closing an electric circuit, and a circuit making and breaking means consisting in sending at least one of said intersecting beams of ionizing short waves intermittently.
10. A system according to claim 9, in which the circuit making and breaking means consists in deflecting at least one of said intersecting beams of ionizing short waves intermittently.
11. A system according to claim 9, in which the circuit making and breaking means consists in interrupting at least one of said intersecting beams of ionizing short waves intermittently.
